UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A SPOON, &c.

SPECIFICATION forming part of Design No. 20,863, dated June 30, 1891.

Application filed May 8, 1891. Serial No. 392,107. Term of patent 7 years.

To all whom it may concern:

Be it known that I, AUSTIN F. JACKSON, residing at Taunton, in the county of Bristol and State of Massachusetts, have invented and produced a new and original Design for Handles of Spoons, Forks, and similar Articles, of which the following is a specification, reference being had to the accompanying drawing, forming a part thereof, and in which 5 the figure is a face view of a spoon the handle of which is designed according to my invention.

The most prominent feature of my design is the handle ornamentation, which consists 10 of a view of an exposition-building.

The minor features of the design consist of the border ornamentalations which surround such building and the transverse ornament forming the base of such border.

15 In the drawing, *a* indicates the building,

b the ornamental border, and *c* the transverse ornamentation. Below the ornament *c* on the shank of the spoon are the words and numerals "World's Fair, Chicago, 1893." These words and numerals may, however, be omitted, 25 as they form no part of my design.

All of the above ornamentations appear upon the handle of a spoon; but it is manifest they may appear on the handles of knives, forks, ladles, &c.

30 What I claim is—

The design for spoons, forks, knives, ladles, &c., consisting of the building ornamentation *a*, the border *b*, surrounding said building *a*, and the transverse ornamentation *c*, all arranged substantially as shown and described.

35 AUSTIN F. JACKSON.
